CLAIM

The ornamental design for a safety railing having a buoy holder, as shown and described.

DESCRIPTION

FIG. 1 is a front perspective view of a fourth embodiment of a safety railing having a buoy holder according to our new and ornamental design;

FIG. 2 is a rear perspective view thereof;

FIG. 3 is rear elevation view thereof;

FIG. 4 is a front elevation view thereof;

FIG. 5 is a side view thereof;

FIG. 6 is an opposite side view thereof;

FIG. 7 is a top view thereof; and,

FIG. 8 is a bottom view thereof.

The broken lines in the drawings illustrate portions of the safety railing having a buoy holder that form no part of the claimed design.
